UNITED STATES PATENT OFFICE.

HERBERT DUMARESQ, OF BOSTON, MASSACHUSETTS.

DESIGN FOR PATTERN FOR CALICOES.

Specification forming part of Design No. **11,167**, dated April 22, 1879; application filed January 21, 1879.
[Term of patent 3½ years.]

To all whom it may concern:

Be it known that I, H. DUMARESQ, of Boston, in the county of Suffolk and State of Massachusetts, have originated and Designed a Pattern for Calico and other Fabrics, of which the following is a full, clear, and exact description, reference being had to the accompanying photographic illustration, making a part of this specification.

The nature of my design is fully represented in the accompanying photographic illustration, to which reference is made.

In said illustration, A represents a background or body, in which is centrally represented a playing-card known as the "ace of spades." Around this card, at a suitable distance, are radially arranged effigies of the face-cards of the several suits—to wit, kings, queens, and jacks of the suits known as "diamonds," "hearts," "clubs," and "spades;" and outside such group or groups are represented pip or spot and face cards, arranged to form lines or stripes. Such central figures or groups are repeated at desired intervals along the fabric.

I have made use of my design upon calicoes known as "cotton prints," upon muslins, woolens, silks, and other fabrics; and it may be

printed or stamped upon, woven into, or otherwise wrought into or represented upon the fabric. I prefer to employ the usual and conventional colors in representing the pips or spots upon the emblematic cards, as also in the figures or faces upon the face-cards; but I do not consider such colors essential elements in my design. Nor do I deem a distinguishing ground color for such groups as of the substance of my design, as such groups may be represented upon the same ground color as the lines or stripes.

I make no claim to the design of the several cards as such, nor do I claim a mere picture wherein a plurality of the cards of a pack are represented; but

What I do claim as my invention is—

A design for calico and other fabrics, composed of the grouped effigies of the face-cards, and with the lines or stripes formed by effigies of spot and face cards along the borders, and in the intervals between such groups, substantially as specified.

HERBERT DUMARESQ.
